UNITED STATES PATENT OFFICE.

GEORGE WATSON, OF LONDON, AND FRANK LESLIE WATSON, OF PERSHORE, ENGLAND.

FIRE-GRAVE FOR REFUSE-DESTRUCTORS AND OTHER FURNACES.

1,050,317.

Specification of Letters Patent.

Patented Jan. 14, 1913.

Application filed August 23, 1912. Serial No. 716,660.

To all whom it may concern:

Be it known that we, GEORGE WATSON and FRANK LESLIE WATSON, subjects of the King of Great Britain, and residents of 5 Ruskin 5 Close, Hampstead Way, London, England, and Pershore, Worcestershire, England, respectively, have invented new and useful Improvements in and Relating to Fire-Grates for Refuse-Destructors and other 10 Furnaces, of which the following is a specification.

Hitherto most of the successful destructors for town refuse have been based upon the principle of intermittent charging and 15 clinkering, and, believing as we do that the intermittent system as opposed to continuous firing is most suitable for such a poor class of fuel as town refuse, we have sought 20 means to avoid the heavy labor and the exposure of the workman to heat involved in practically all the systems of drawing the clinker hitherto employed. The charging of such furnaces is sometimes instantaneous when mechanical means of charging are employed and sometimes by stages, when hand 25 feeding is adopted, but in either case there results at the end of each burning period a mass of hot and often molten clinker on the grate which must be removed from the furnace in order to start a fresh fire. On withdrawing the mass of clinker it is necessary to leave within the furnace and ready to 30 spread over the clean grate, so much hot cinders and other fuel not completely vitrified, as may be necessary to ignite rapidly and thoroughly the next charge. It is this 35 operation which has up to now seemed to demand the hand-skill and intelligent care of the workman and which has prevented 40 the use of a mechanical grate of the various known types. Bearing in mind that the mass of hot clinker may, in some instances weigh as much as or more than half a ton, and that it is desirable to draw it as quickly 45 and as possible so as not to interrupt the working of the furnace any longer than is necessary nor permit the interior of the furnace to cool down, manufacturers have in some cases provided movable grates capable of 50 traveling on wheels to and from the furnace. We also provide a movable grate mounted on wheels but the arrangement is such that it can be tipped like a tipping trolley. It is also furnished with means of applying the 55 blast and is provided with appliances for keeping it cool.

In the accompanying drawing we have illustrated a movable grate in the form we prefer to employ fitted to a refuse destructor of well known type. 60

Figure 1 is a sectional elevation and Fig. 2 is a cross section.

In the arrangement shown the grate consists of a tipping truck *a* mounted on four flanged wheels *b* running on rails *c* laid into the ashpit *d* and designed so as to pass easily into and out of the furnace *e* and to fit loosely between the side walls *f* of the furnace which may be made to overhang or offset inward above the tipping truck as shown, 70 thus causing all refuse fed into the furnace eventually to fall into the tipping truck and not over the edge thereof. The blast of air produced by any known means such as a blower fan or steam jet apparatus is admitted to the interior of the truck below the grate by means of a detachable connection in a manner hereinafter more fully described. 75

In the furnace at the back of the tipping truck, or it may be otherwise situated if desired, is a deadplate or a hearth *g* close to which the truck is pushed. Means for locking the truck firmly in position in the furnace may be provided but are not shown in the drawing. 80

The furnace being fed in the usual manner, the refuse will at first fill the interior of the furnace room for a considerable height above the truck, the refuse lying 90 against the overhanging walls of the furnace. But as it burns down it will constantly fall into the truck and fuse down into clinker in which form it occupies only one quarter of its original bulk. When the fire 95 has reached that stage when most of the refuse is converted into clinker and only a small quantity of unfused cinders and refuse remains on the top of the clinker the stoker will open one or more of the doors *h* fixed 100 in the front wall of the furnace above the tipping truck, and push back the loose cinders and other burning fuel from off the top of the clinker on to the deadplate or hearth *g*. This will leave the clinker level 105 or approximately level with the top edge of the tipping truck which is then ready to be drawn out and emptied. When the tipping truck is in position it forms part of the furnace and the ashpit may be closed by 110 means of a door, not shown in the drawings, which may or may not be attached to the

truck or may be separately mounted. To remove the truck or grate this door, if there is one, is first opened and the blast is cut off from the truck or grate by suitable means. 5 The tipping grate or truck is then drawn or pushed out on its rails in the direction of the arrow either by hand, or by suitable mechanical means; and taken to the clinker cooling yard, where it may be at once tipped 10 and discharged. The same truck or another empty one in readiness is then run into the ashpit, and the loose fire from off the dead-plate at the back is drawn forward by the workman raking through the rake door or 15 doors *h* before mentioned and spread in the bottom of the tipping truck or grate. The new charge is then put into the furnace and descends upon the hot fire in the bottom of the tipping truck. The blast is connected 20 again and turned on and the fire soon again burns up.

On referring to the drawings it will be seen that a tipping truck is provided with a double bottom, the air space between 25 the inner and the outer casing being connected with the blast *i*. The outer casing *j* is solid and the inner casing *k* is provided with suitable holes or airspaces for admitting the blast to play upon the fire in the 30 truck, this inner casing *k* thus forming the grate. If preferred however a twyer may be laid in the bottom of the tipping truck or grate to apply the blast. By passing the air for combustion between the outer shell 35 and inner shell forming the grate of the tipping truck, the double purpose is served of warming air for combustion and also protecting the truck or grate from damage by the heat of the fire.

40 To prevent distortion by the heat, we prefer to make the shells or casings of the tipping truck or one of them corrugated form, in the drawings the outer shell or casing *j* is shown thus formed.

45 In the case where a twyer is used its construction will depend on circumstances such as the pressure of the blast required and the nature of the fuel.

In the drawings a pipe *m* is shown fitted 50 to the truck which pipe may be used for introducing either water or steam between the casings.

The blast pipe is connected to the tipping truck by a detachable joint and if in front 55 the blast pipe may be suitably hinged or made of metallic flexible hose pipe so that it may be disconnected or removed when the truck has to be drawn from the ashpit.

Another convenient method of connecting 60 the blast pipe is, as shown in the drawings, through the back of the furnace. In this case the back wall of the furnace is provided with a cone-shaped nozzle *i*, the orifice of

which is inside the wall and fits tightly into a port *l* in the tipping truck when the latter 65 is pushed up hard against it. The tipping truck may be held in this position under pressure from a clamping screw or lever, not shown, working through the front door of the ashpit. In this construction the blast 70 pipe may be provided with a valve which can be turned off when the tipping truck is temporarily removed.

It is obvious that numerous changes might be resorted to in the structure and arrangements of the parts without departing from the spirit and scope of the invention. 75

We have described our invention particularly as relating to refuse destructors, but any furnace where intermittent or successive burning is required may be conveniently fitted with the moving grate and other attachments according to our invention. The actual construction of the tipping truck which constitutes the movable grate is capable of wide variation and it is therefore thought unnecessary to describe or illustrate in detail any one form. 85

What we claim and desire to secure by Letters Patent of the United States is:— 90

1. In a refuse destructor or similar furnace having a combustion chamber, the combination of a wheeled carriage, a grate carried thereby and removable therewith from the furnace, said grate being the sole grate 95 provided for said combustion chamber, and a dead plate or hearth located above the removable grate aforesaid and adapted for coöperative relation therewith and for retaining heated cinders when the carriage is 100 removed from the furnace.

2. In a refuse destructor or similar furnace having a combustion chamber, the combination of a wheeled carriage, a grate carried thereby and removable therewith from 105 the furnace, the carriage being provided with a closed chamber below the said grate, said grate being the sole grate provided for said combustion chamber, and air blast supply means positioned and adapted to direct 110 an air blast to the closed chamber when the carriage is in position for the grate to constitute the grate of the combustion chamber.

In testimony whereof we have signed our names to this specification in the presence 115 of two subscribing witnesses.
